UNITED STATES PATENT OFFICE.

WILLIAM O. SHELDON, OF LAKEWOOD, OHIO, ASSIGNOR TO THE YODER COMPANY, OF CLEVELAND, OHIO, A CORPORATION OF OHIO.

PROCESS OF MAKING SHEET-METAL FRAMES.

Application filed June 23, 1925. Serial No. 39,077.

This invention relates to a process of making frames for mounting sheet material, panels, wire screens and the like, whereby the sheet is supported along its sides and ends and a unitary structure is provided, thus enabling the sheet to be handled and supported in various ways. The invention has reference to the process of making frames from sheet metal and the object of the invention is to provide a relatively simple process whereby speed of operation and increased output is obtained, and the assembly of the sections of the frame greatly facilitated.

Other objects of the invention will be apparent to those skilled in the art to which my invention relates from the following description taken in connection with the accompanying drawings, wherein I have shown one form of shaping and bending elements suitable of performing the steps of my process.

In these drawings,

Fig. 1 is a plan view of a section of sheet metal showing its shape following the carrying out of the first step of my process.

Figs. 2, 3, 4, 5, 6, and 7 are elevational views of suitable shaping elements showing the successive operations or steps in making the frame.

Fig. 8 is a plan view of a frame in assembled position. In this latter figure I have shown a complete frame 1 having side segments 1^a and end segments 1^b, which segments form the framing for a wire screen or a suitable panel, sheet of material and the like which is to be mounted and supported for handling purposes.

Fig. 9 is an end view of the frame.

Fig. 10 is a section on the line 10—10 of Figs. 8 and 9.

In carrying out the first step of my process, I take a strip of sheet metal of the desired gauge and cut it into lengths or sections 2 each equalling the aggregate length of the segments 1^a, 1^a, 1^b, 1^b, which constitute the sides and ends of the mounting frame indicated as an entirely at 1 in Fig. 8; and I also cut in the opposite longitudinal edges of the section 2 aligned V-shaped notches 2', the apexes of which are aligned with each other and coincide with imaginary longitudinal lines 2^a, which are parallel and spaced apart a distance equal to the width 55 of the end walls 3 of the completed frame 1.

The pairs of V-shaped notches 2' are spaced from each other and from the opposite ends of the section according to the length of each frame segment, so that when the section is bent on transverse lines 13, cutting the apexes of the V-shaped notches 2', they will co-operate to form the frame 1. In carrying out this step, the metal strip may be passed between suitable cutting rolls or it may be stamped out to the desired shape and size, the ends being cut on lines corresponding to the sides of a V-shape notch, so that when the two ends abut they constitute one corner of the frame 1.

Next I pass the section 2 between a pair of rolls 4, one having in its circumference midway between its side edges a V groove 4^a and the other having a correspondingly arranged complementary V rib 4^b, which co-act to roll a V-shaped wall 5 in the section 2, from end to end thereof, the apex of the groove being centrally of the lines 2^a and the lateral edges of the V wall 5 being coincident with said lines. Next, I pass the section 2

between a pair of rolls 6 the peripheries of which correspond in shape to the peripheries of the rolls 4, but one thereof is provided with flanges 6^a, which bend upwardly the longitudinal edges of the section 2 between adjoining notches 2' and the outer notches 83 and the ends of the section to form end walls 7. Next, I pass the metal section 2 between a pair of rolls 8 whose peripheries correspond in shape with the peripheries of the rolls 4 and 6, except that their walls 8^a at

either side of the complementary groove 4^a and rib 4^b are complementary shaped to bend the section 2 on the longitudinal lines 2^a to position the portions or walls 8^b between the V-shaped wall 5 and end walls 7 at angles 95 to each other as shown in Fig. 4. Next, I pass the metal section 2 through a pair of rolls 9 having a complementary groove 4^a and rib 4^b, but having complementary walls 9^a at either side of the groove 4^a and rib 100 4^b arranged to bend the section 2 along the lines 2^a to decrease the angular relations between the portions 8^b, as shown in Fig. 5, and to bring the end walls 7 into closer relationship.

Next, I pass the section of metal 103 2 between a pair of rolls 10 having a complementary groove 4^a and a complementary groove 4^b and one of which is provided with peripheral bending walls 10^a which engage the portions 8^b of the section 2 to further 110

bend them along the lines 2^a to further decrease the angular relation between them and to move the end walls 7 into still closer relationship for the final operation. Next, I 5 pass the section 2 between a pair of rolls 11, 11^a, one of which is provided with a peripheral groove 11^b having a width corresponding to the width of each segment of the frame 1 and the other of which is provided with a 10 rib 11^c which fits within the groove 11^b to engage the formed section 2, the side walls of the groove 11^b serving to bend the portions 8^b along the lines 2^a into parallel relationship and the periphery of the rib 11^c 15 engaging with the side walls 7 and through them forcing the section inwardly of the roll 11 to insure final shaping of the walls 8^b, and simultaneously while shaping the section 2 between the rolls 11, 11^a, I straighten 20 the walls 3 to make it flat from side edge to side edge and space the end walls 7 from each other, this step being performed by an annular wall 12 provided on the rib 11^c and disposed midway between the side edges 25 thereof.

As shown in Fig. 7, this rib projects inwardly between the end walls 7 in line with the apex of the rib 5 and engages therewith to roll the walls of the rib 5 outwardly or 30 flat against the bottom wall of the groove 11^b. The wall 12 is preferably equal in width to the panel or sheet which is to be supported by and mounted in the frame 1 and accordingly it spaces the end edges of 35 the end walls 7 apart sufficiently to permit the insertion of the panel in the final assembly of the frame.

Finally, I bend the section 2 on the transverse lines 13, which coincide with the apexes 40 of the V-shaped grooves 2', to bend the frame segments at substantially right angles to each other and position the panel between the end walls with its free edges disposed within the segment walls; following which I solder 45 the ends 14 of the section to each other to complete the frame 1 with the panel mounted within. In positioning the frame segments, the notches 2' permit their side walls to abut end to end to complete the corners and provide a smooth continuous surface around the frame 1. The sheet or panel is preferably cut to a size to fit within the walls 3.

For illustrative purposes I have shown a frame 1 having segments each of which is 55 of substantially rectangular shape in cross section, but it will be obvious that the cross sectional shape thereof may be changed in various ways. It will also be obvious that either end of the section 2 may be provided 60 with an extension which may overlap the opposite end thereof when the frame is finally completed and assembled to more securely hold the ends together.

My invention is advantageous since all the 65 sides of the frame 1 are made from a single

section of material. By my process the manufacture and assembly of the frame is facilitated since the several sides or segments thereof are unitary. By making all the segments of the frame from one strip of material the sections are long enough to pass between the several pairs of shaping rolls; hence the labor and number of required operations are materially reduced.

In my process I eliminate all waste of 75 material (except that resulting from the forming of the notches 2') for two reasons, (1) none of the walls have overlapping portions or extensions usually required to hold them in bent-up position and relation and 80 (2) the strip may be cut to the exact shape required in forming the complete frame. By using a minimum amount of material, I am enabled to reduce the weight of the frame.

To those skilled in the art to which my invention relates widely differing embodiments of my invention will suggest themselves without any departing from the spirit and scope thereof. My disclosures and the 90 description herein are purely illustrative and not intended to be in any sense limiting.

While I prefer to pass the sections 2 through several sets or pairs of rolls to bend the side walls 8^b into parallel relation, it is 95 obvious that they may be positioned with a lesser number of passes, if desired.

What I claim is:

1. The herein disclosed process of making frames for panels, sheets and the like, which 100 consists in first forming a sheet metal strip into sections of predetermined length each section having pairs of V-shaped notches in its side edges spaced from each other and from the ends of the strip to form the sides and ends of the frame, then in forming longitudinally of the strip midway between its side edges a V-shaped groove, then in forming along its longitudinal side edges end walls, then in bending the side walls between said groove and said end walls toward each other along the lateral edges of said V-shaped groove, then in straightening the walls of the V-shaped groove to form the outer end walls of the frame and moving the side walls toward each other to position the inner end walls, then in bending the strip on transverse lines coincident with the apexes of the V-shaped notches, and finally 110 associating a panel or sheet between the inner end walls and connecting the ends of the strip together.

2. The herein disclosed process of making frames for panels, sheets and the like, which 120 consists in first forming a sheet metal strip into sections of predetermined length each section having pairs of V-shaped notches in its side edges spaced from each other and from the ends of the strip to form the sides and ends of the frame, then in forming 125

- longitudinally of the strip midway between its side edges a V-shaped groove, then in forming along its longitudinal side edges end walls, then in bending the side walls between said groove and said end walls toward each other along the lateral edges of said V-shaped groove, and then in straightening the walls of the V-shaped groove to form the outer end walls of the frame and moving the side walls toward each other to position the inner end walls, and finally in bending the strip on transverse lines coincident with the apexes of the V-shaped notches.
- 15 3. The herein disclosed process of making frames for panels, sheets and the like, which consists in first forming a sheet metal strip into sections of predetermined length each section having pairs of V-shaped notches in its side edges spaced from each other and from the ends of the strip to form the sides and ends of the frame, then in forming longitudinally of the strip midway between its side edges a V-shaped groove, then in forming along its longitudinal side edges 25 end walls, then in bending the side walls between said groove and said end walls toward each other along the lateral edges of said V-shaped groove, then in straightening the walls of the V-shaped groove to form the 30 outer end walls of the frame and moving the side walls toward each other to position the inner end walls and spacing the free edges of the end walls from each other, and finally bending the strip on transverse lines 35 coincident to the apexes of the V-shaped notches to position the sides and ends of the frame at angles to each other.
- 20 In testimony whereof, I have hereunto subscribed my name.

WILLIAM O. SHELDON.
